UNITED STATES PATENT OFFICE.

RICHARD C. STONE, OF ST. LOUIS, MISSOURI.

GRAIN BLENDING AND DISTRIBUTING APPARATUS.

Application filed January 25, 1923. Serial No. 614,730.

To all whom it may concern:

Be it known that I, RICHARD C. STONE, a citizen of the United States of America, and a resident of the city of St. Louis, in 5 the State of Missouri, have invented certain new and useful Improvements in Grain Blending and Distributing Apparatus, of which the following is a full, clear, and exact description, reference being had to 10 the accompanying drawings, forming a part of this specification.

This invention relates to improvements in grain blending and distributing apparatus, one of the objects being to provide a simple 15 means whereby grain passing from different parts of a grain elevator may be selectively delivered to different grain bins or to other parts of the elevator. A further object is to provide an apparatus of this kind in which grain from different sources can be mixed 20 or blended while it is passing through the apparatus. It will also be understood that different kinds of grain can be very conveniently mixed while passing through the 25 apparatus.

Another object of the invention is to minimize the labor and expense of transferring grain from one point to another, for example, from elevator legs or grain cleaners 30 to the grain bins, or from grain bins to elevator legs.

The preferred form of the invention includes a grain distributing and blending receptacle having two compartments, and 35 discharged spouts leading from the respective compartments. Each discharge spout may be adjustable in an arc of a circle to locate its discharge end in different positions, hereby allowing the grain to pass from either 40 compartment to any one of a number of grain bins, or other receptacles. Each compartment of the distributing receptacle may be provided with a number of intake spouts leading from different elevator legs, or from 45 different cleaners, or these intake spouts may lead from various other sources. It will now be understood that grain from various 50 different sources may be simultaneously delivered to one of the distributing compartments and from thence to any one of a number of grain bins, or when desirable, the grain passing from only one of the intake spouts may be delivered to any selected 55 grain bin. Furthermore, grain from several different sources can be simultaneously delivered to the respective distributing com-

partments and then through the adjustable discharge spout to the selected bins.

In addition to the foregoing, the apparatus preferably includes one or more valve 60 devices whereby the grain passing from an intake spout may be directed into either distributing compartment. In using the apparatus, the discharge spouts are adjusted 65 to deliver the grain to the selected bins, and by adjusting the valve device herein shown it is possible to direct the grain from any one or more of the intake spouts to either discharge spout. There are several intake 70 spouts which may be placed in communication with either discharge spout.

The variations obtainable in the distribution and blending of the grain are so numerous that I will not specifically point 75 out the results or advantages of all of the different adjustments which may be made in the apparatus. It will be understood, however, that it is highly desirable to blend different grains, and that it is likewise desirable to minimize the labor and expense in 80 transferring grain from various points to certain selected points at lower elevations. After the source of the grain has been determined, the delivery point can be very 85 easily selected by merely adjusting a discharge spout and a valve, and in many instances it will not even be necessary to adjust the valve. Moreover, different grades of grain, or different kinds of grain, can be 90 blended or mixed while they are passing to the selected delivery point, and it is possible to blend different streams of grain passing to one of the discharge spouts while one or more additional streams of grain are passing 95 to the other discharge spout.

With the foregoing and other objects in view, the invention comprises the novel construction, combination and arrangement of parts hereinafter more specifically described and illustrated in the accompanying 100 drawings wherein is shown the preferred embodiment of the invention. However, it is to be understood that the invention comprehends changes, variations and modifications 105 which come within the scope of the claims hereunto appended.

Fig. I is a top or plan view of an apparatus embodying the features of this invention, the intake spouts being shown in section, 110 and the upper and lower margins of the receptacle being broken away.

Fig. II is a vertical section of the appa-

ratus, showing the floor to which the receptacle is secured.

Fig. III is a horizontal section on a small scale, illustrating a number of grain bins adapted to receive the grain passing from my apparatus, the combined blending and distributing apparatus being shown in elevation.

Fig. IV is an enlarged fragmentary vertical section illustrating the antifriction bearing whereby one of the discharge spouts is rotatably supported.

Fig. V is a view similar to Fig. IV showing the antifriction bearing associated with the other discharge spout.

A designates a combined blending and distributing receptacle comprising an outer compartment 1 and an inner compartment 2 surrounded by said outer compartment, a cover 3 being arranged over both compartments, as shown most clearly by Fig. I. This double receptacle is secured to a stationary floor 4 (Fig. II) by means of bolts 4' passing through a flange 3' which extends from the outer compartment. The double receptacle is thus secured in a fixed position.

The inner receptacle 2 (Fig. II) is provided with a hopper bottom and a stationary spout section 5 extending downwardly therefrom. 6 designates an angular discharge spout telescoping with and inclined downwardly from the spout section 5. A ball bearing 7 (Figs. II and V) is interposed between the telescoping portions of these spout members, the balls being confined between a ring 8 at the lower end of spout section 5 and a ring 9 at the upper end of discharge spout 6. A vertical supporting rod 10 (Fig. II), alined with the axis of spout section 5, is secured in a socket 11 attached to the discharge spout 6, and the lower end of this vertical rod is rotatably mounted in a stationary bearing 12. 13 designates a stay, or brace, connecting the lower portion of discharge spout 6 to the vertical rod 10. The discharge spout 6 is thus rigidly secured to the rotatable rod 10, and the upper end of said spout 6 is rotatable on the lower end of the stationary spout section 5. The lateral thrusts resulting from the overhanging weight of discharge spout 6, are transmitted to the ball bearing 7, so the spout 6 will turn freely about the axis of the stationary spout section 5.

The outer compartment 1 is provided at its lower end with a horizontal flange 14 forming a raceway for a ball bearing 15, as shown by Figs. II and IV. An angular discharge spout 16 is inclined downwardly from the lower end of the outer compartment 1, and an annular raceway member 17 is secured to the upper end of said spout, as shown by Figs. II and IV, said member 17 being extended inwardly so as to overlie

the ball bearing 15 on the raceway 14. The discharge spout 16 is free to turn on the ball bearing 15, and its axis of rotation preferably coincides with the axis of stationary spout section 5. 18 designates an inclined supporting device connecting the overhanging portion of spout 16 to the raceway member 17. The weight of the overhanging spout 16 may be counterbalanced by a weight 19 mounted on an arm 20 which extends from the raceway member 17.

To prevent leakage of grain between discharge spout 16 and spout section 5, the spout 16 is provided with an internal tubular guard member 21 (Fig. II) and a deflector 22 is secured to the stationary spout section 5. The deflector 22 overlaps the upper end of the tubular guard member 21, and the latter is secured to the rotary discharge spout 16.

Intake spouts 23 and 24 are secured to the top wall of the inner compartment 2, and the grain passing from these spouts may be discharged directly into said inner compartment. 25 designates intake spouts leading into the top of the outer compartment 1. Valve housings 26, preferably located in the receptacle A, are open at the top and bottom so as to provide communication between the spouts 24 and 25 and the compartments 1 and 2. The upper end of each valve housing 26 is in direct communication with a spout 24 and a spout 25, while the lower end of each valve housing is in communication with the compartments 1 and 2. 27 designates deflector valves located in the respective valve housings 26 and pivotally supported by rods 28. These pivotally mounted valves can be moved from the positions shown by full lines in Fig. II to the positions shown by dotted lines. These valves 27 may be operated independently of each other, and they may be located in upright positions midway between the positions illustrated in Fig. II. When a valve 27 occupies either of the inclined positions shown by Fig. II, its upper end engages a stationary flange 29 which prevents leakage of grain between the upper end of the valve and the adjacent wall of the valve housing.

Operating knobs 27' are secured to the valves 27 as shown in Fig. II, and the top wall 3 is provided with openings 27a (Fig. I) through which a person's hand can be inserted to operate the valves.

When the valves 27 occupy the positions shown by dotted lines in Fig. II, the grain passing from the lower ends of spouts 24 will be diverted into the outer compartment 1, and thence to the discharge spout 16 which is at all times in communication with the outer compartment. When these valves occupy the positions shown by full lines in Fig. II, the grain passing from intake spouts 25 will be diverted into the inner

compartment 2 and thence to the rotary discharge spout 6. When the valves 27 occupy vertical positions midway between the positions shown in Fig. III, all of the grain 5 passing through intake spouts 24 will be conducted to the discharge spout 6, and the grain passing from intake spouts 25 will be delivered to the discharge spout 16.

From the foregoing it will be readily 10 understood that the valves 27 may be adjusted independently of each other, and the grain passing from any one of the intake spouts 24 and 25 can therefore be directed to either of the discharge spouts 6 and 16. The 15 various intake spouts 24 and 25 may lead from different receptacles in a grain elevator. For example, some of the spouts may lead from elevator heads, and others may lead from grain cleaners. By properly adjusting the valves 27, the grain passing from 20 any one or more of the intake spouts 24 and 25 can be delivered to the discharge spout 16, and at the same time grain passing from other intake spouts may be delivered to the 25 discharge spout 6.

Fig. III shows a number of grain bins 30 and 31 adapted to receive the grain passing from the discharge spouts 6 and 16. The 30 combined blending and distributing apparatus may be surrounded by grain bins, as shown in Fig. III, which lie at a lower elevation than the discharge spouts. Each grain bin 30 is provided with an intake opening 30', and each bin 31 is provided with an 35 intake opening 31' communicating with a pocket 32. Each discharge spout 6 and 16 may be adjusted in an arc of a circle so as to discharge its contents into any one of the grain bins 30 and 31. It will thus be seen 40 that the grain to be blended or distributed may be taken from various sources through the intake spouts 24 and 25 and delivered through the discharge spouts to any selected grain bin.

45 I claim:

1. The combination of a plurality of adjustable grain-spouts, a distributing receptacle through which the grain is delivered to said adjustable spouts, said receptacle having 50 inlets for grain from different sources, and means supported by and located at the discharge end of said distributing receptacle whereby the grain passing into any of said inlets may be selectively directed 55 into any of said spouts.

2. The combination of a grain distributing receptacle having two compartments, discharge spouts leading from the respective compartments, each of said discharge 60 spouts being movable in an arc of a circle to locate its discharge end in different positions, each of said compartments having an inlet for the admission of grain, and means whereby the grain may be diverted 65 from the inlet of one of said compartments

to the discharge spout of the other compartment.

3. The combination of a grain distributing receptacle having two compartments, discharge spouts leading from the respective 70 compartments, each of said discharge spouts being movable in an arc of a circle to locate its discharge end in different positions, each of said compartments having an inlet for the admission of grain, said compartments 75 being in direct communication with each other, and a valve device adapted to divert the grain from the inlet of one compartment to the discharge spout of the other compartment.

4. The combination of a grain distributing receptacle having an inner compartment and an outer compartment, discharge spouts leading from the respective compartments, each of said discharge spouts being movable in an arc of a circle to locate its 80 discharge end in different positions, each of said compartments having an inlet for the admission of grain, and means whereby the grain may be diverted from one of said compartments 85 to the other compartment.

5. The combination of a grain distributing receptacle having an inner compartment and an outer compartment, discharge spouts leading from the respective compartments, 90 each of said discharge spouts being movable in an arc of a circle to locate its discharge end in different positions, each of said compartments having an inlet for the admission of grain, and a valve device 95 whereby the grain may be diverted from the intake of one compartment to the discharge 100 spout of the other compartment.

6. The combination of a grain receptacle having two compartments, intake spouts leading to the respective compartments, discharge spouts leading from the respective compartment, each of said discharge spouts being movable in an arc of a circle to locate 105 its discharge end in different positions, and means for diverting the grain from the intake spout of one compartment to the discharge spout of the other compartment, said means including a valve device movable from an inclined position directly below one of said intake spouts to an inclined position directly below the other intake spout, and said compartments being in communication with each other at said valve device to provide for the delivery of grain from one 110 compartment to the other.

7. The combination of a grain distributing receptacle having two compartments, discharge spouts leading from the respective compartments, each of said discharge 115 spouts being movable in an arc of a circle to locate its discharge end in different positions, each of said compartments having an inlet for the admission of grain, a valve housing in said distributing receptacle, said 120

valve housing being in communication with both of said compartments, and a deflector valve located in said valve housing to control communication between the inlets and discharge spouts, said deflector valve being adapted to place the inlet of one compartment in communication with the discharge spout of the other compartment.

8. The combination of a grain receptacle having two compartments, intake spouts leading to the respective compartments, discharge spouts leading from the respective compartments, each of said discharge spouts being movable in an arc of a circle to locate its discharge end in different positions, a valve housing in said distributing receptacle, said valve housing being in communication with all of said spouts, and a deflector valve located in said valve housing to permit communication between the intake spout of one compartment and the discharge spout of the other compartment.

9. The combination of a grain distributing receptacle, a plurality of intake spouts leading to said receptacle, a plurality of discharge spouts leading from said distributing receptacle, and selective means whereby any of said intake spouts may be placed in communication with any of said discharge spouts, said selective means comprising a plurality of deflector valves each of which is adapted to control communication between two intake spouts and the discharge spouts.

10. The combination of a grain distributing receptacle, a plurality of intake spouts leading to said receptacle, a plurality of discharge spouts leading from said distributing receptacle, valve housings in said distributing receptacle, each of said valve housings being in communication with said discharge spouts and also with two of said intake spouts, and deflector valves in the respective valve housings, each of said deflector valves being movable to place any of the intake spouts associated therewith in communication with any of said discharge spouts.

11. The combination of a grain distributing receptacle, a plurality of intake spouts leading to said receptacle, a plurality of discharge spouts leading from said distributing receptacle, valve housings in said distributing receptacle, each of said valve housings being in communication with said discharge spouts and also with two of said intake spouts, and deflector valves in the respective valve housings, each of said deflector valves being movable to place any of the intake spouts associated therewith in communication with any of said discharge

spouts, and each of said discharge spouts being movable in an arc of a circle to locate its discharge end in different positions.

12. The combination of a grain distributing receptacle having a plurality of intake openings and a plurality of discharge openings, intake spouts leading to said intake openings, discharge spouts leading from said discharge openings, grain bins below said discharge spouts, each of said discharge spouts being movable in an arc of a circle to locate its discharge end in different positions for the delivery of grain to the different bins, and means whereby the grain passing into any of said intake openings may be directed into any of said discharge spouts, said means including deflector valves located in said distributing receptacle so as to permit communication between any selected intake spout and any selected discharge spout. 80

13. The combination of a grain distributing receptacle having two compartments, discharge spouts inclined downwardly from the respective compartments, and means whereby said discharge spouts are rotatably secured to the respective compartments, said means including a stationary spout section extending downwardly from one of said compartments and passing through one of said discharge spouts and said stationary 90 spout section telescoping with another of said discharge spouts, and antifriction bearings interposed between the telescoping portions of the last mentioned discharge spout and said spout section. 95

14. The combination of a grain distributing receptacle having two compartments, discharge spouts inclined downwardly from the respective compartments, and means whereby said discharge spouts are rotatably secured to the respective compartments, said means including a stationary spout section extending downwardly from one of said compartments and passing through one of said discharge spouts and said stationary 100 spout section telescoping with another of said discharge spouts, and antifriction bearings interposed between the telescoping portions of the last mentioned discharge spout and said spout section, said means including a horizontal annular flange extending from one of said compartments, a horizontal annular flange extending from one of said discharge spouts, and antifriction bearings interposed between said flanges to permit 110 free rotation of the last mentioned spout. 115

In testimony that I claim the foregoing I hereunto affix my signature.

RICHARD C. STONE.
